UNITED STATES PATENT OFFICE.

UNO L. SUNDBLAD, OF NEW HAVEN, CONNECTICUT, ASSIGNOR OF ONE-HALF TO
CHARLES W. WELLS, OF NEW HAVEN, CONNECTICUT.

ELECTRICALLY-WOUND TIMEPIECE.

Application filed March 25, 1926. Serial No. 97,835.

Fig. 1 is a rear view of an electrically-wound time-piece constructed in accordance with my invention.

Fig. 2 is a side view of the same.

Fig. 3 is a rear view with the back-plate of the casing partly broken away and the parts shown in the closed-circuit position.

Fig. 4 is a similar view with the parts shown in the circuit-open position.

Fig. 5 is a side view with the case in section.

Fig. 6 is a view thereof in vertical, central-longitudinal section.

This invention relates to improvement in electrically-wound time-pieces, and while adapted for various purposes, this device is particularly designed for a small, watch-like time-movement commonly used on automobiles.

Among the objects of this invention are to provide winding-means for time-pieces which will be periodically actuated to rewind the spring of the time-piece, rewinding being controlled by the tensional condition of the spring, so that accurate and reliable rewinding is obtained without interference with the normal running of the time-piece; to provide a compact, closed mechanism which may be readily attached to and detached from the time-piece casing; to provide an improved motor transmission and driving mechanism; to so compact and arrange the winding mechanism that it can be enclosed in a case within the peripheral limits of the movement-casing; and to generally provide new and improved mechanism for the accomplishment of the above objects, and the invention consists in the construction as hereinafter described and particularly recited in the claims.

In carrying out my invention, I employ a motor consisting of the usual armature 10 and field-coils 11. This armature has a hollow shaft 12 mounted in bushings 13 and 14 respectively mounted in plates 15 and 16 which are spaced apart by a ring-like field-magnet 17. These are enclosed in a shell 18 secured to the rear of a time-movement-casing 19 of any preferred construction except that of the spring-winding arbor, which includes a comparatively large winding gear-wheel 20. Meshing with this gear-wheel 20 is a small pinion 21 fixed to the end of a spindle 22 which extends through the center of the hollow shaft of the arma-

ture, and its rear end 23 is threaded. The rear end 24 of the hollow shaft is also externally threaded. Screwed onto the end of the hollow shaft of the armature is a segmental plate 25. Pivoted to the forward face of this plate is a pivotal switch-arm 26 carrying on its inner face a contact-brush 27 adapted, when the arm is turned, to contact with a ring 28 mounted on the bushing 14 but insulated therefrom and connected by a wire 29 with the field-coils 11. The plate 25 is also provided on its rear face with a pin 30 which projects through a slot 31 formed in a disk 32 fixed to the rear end 23 of the spindle 22. Fixed at one end to the rear face of the disk, diametrically opposite the slot 31, is a spring 33, the other end of which projects into the path of the pin 30. Fixed to the forward face of the disk is a detent 34 having an angular end 35 to engage with a notch 36 in the arm 26 on the plate 25. On the hollow shaft of the armature is a bowed spring-washer 37 bearing against the segmental plate 25 to insure a good electrical connection between it and the shaft of the armature. On the armature-shaft is a ratchet-wheel 38 engaged by a pawl 39, so that while free to turn in one direction, the shaft will be held against movement in the opposite direction, thus preventing unwinding. As described, one terminal of the field-coils is connected by the wire 29 with the insulated ring 28, while the other terminal of the field-coils is connected by a wire 40 with a plate 41 mounted on an insulating block 42 attached to the rear plate 16. Also attached to this block 42 is a contact-finger 43 connected to the other plate 41 by a fuse 44, that finger engaging with a binding-post 45 mounted in the rear wall 46 of the shell 18 and insulated therefrom. The rear face of the shell is also provided with a binding-post 47 in electrical contact with the shell, thus completing an electric circuit through the motor.

Assuming that the time-piece is in condition to be re-wound, the parts will stand in the position shown in Fig. 3 of the drawings, and assuming that the binding-posts are connected with suitable sources of electric power and the contact-brush being in contact with the ring 28, the circuit is thus completed through the field-coils and the armature will turn. In turning, the armature drives the segmental disk 25, and the pin 30,

engaging with the spring 33, turns the disk 32 and this disk, being fixed to the spindle 22 and its pinion, turns the winding-gear 20 to energize the main-spring.

5 When the time-movement spring is wound to a predetermined point, its resistance to being wound will bend the spring 33 and cause a relative movement between the segmental plate and disk, and this movement 10 of the segmental plate with respect to the disk causes the switch-arm 26 to move under the detent 34, so as to move the brush out of engagement with the disk 28, thus breaking the circuit and stopping the motor, and the 15 angular outer end 35 of the detent snaps into the notch 36 and locks the arm.

The time-movement, acting under the pressure of its spring, will run until the pressure of that spring is so reduced that 20 the spring 33 is able to reassert itself and move the segmental plate 25 relative to the disk and in moving this segmental plate, the notch of the arm 26 is disengaged from the detent and the brush is snapped into engagement with the disk 28 by the engagement of the forward end of the detent with the end of the arm. The circuit through the 25 motor is thus again established and the re-winding operation takes place when the 30 cycle of breaking the circuit is again repeated, and so on.

By providing the armature with a hollow shaft and arranging the winding spindle through it, the movement of the armature 35 is transmitted directly and, consequently, with saving of space, as well as elimination of gearing, and the power from the arbor of the main-spring is used to connect and disconnect the motor. Furthermore, with 40 this arrangement of parts, the running of the time-movement is in no wise interfered with.

If desired, and to avoid gumming the lubricant around the pivot 48 on which the 45 switch-arm 26 oscillates, due to passage of electricity through it, I attach to the outer end of this switch-arm a light wire 49, which is looped and soldered to the segmental-plate 25, thus directing the electric 50 current through the wire to the segment, independent of the connection through the pivot.

I claim:

1. The combination with a time-piece, 55 having a winding-arbor-gear, of an electric motor having a shaft, an electric circuit for the motor, a spindle extending through said shaft, a pinion on said spindle meshing with said gear, a segmental plate carried by the motor-shaft and provided with a pin, a disk carried by said spindle and formed with a slot through which said pin extends, a spring-arm secured to said disk and extending into engagement with said pin, and a

circuit-making-and-breaking brush carried 65 by said plate, said brush moved in one direction by the tension of the winding-spring and in the other direction by the tension of the said spring-arm.

2. In combination, a spring, winding 70 mechanism therefor including a motor, transmission operatively interposed between said spring and motor including a pair of rotatable members, yielding means associated with said members, said members being relatively movable, said yielding means normally resisting such relative movement and a switch actuated by the relative movement between said members to open or close 75 the circuit for said motor.

3. In combination, a spring winding mechanism therefor including a motor, transmission operatively interposed between said motor and spring and comprising a winding spindle, a rotatable disk carried 80 thereby, a driving member actuated by said motor, a spring carried by said disk and means carried by said driving member engaging said spring and transmitting its driving effect therethrough to said disk, 85 said last named means comprising a pin carried by said rotatable member, said disk being slotted to accommodate said pin, said slot being constructed to permit movement 90 of said pin relative to said disk.

4. The combination with a winding-arbor-gear, of an electric motor having a shaft, an electric circuit for the motor, a spindle extending through said shaft, a pinion on said spindle meshing with said gear, a plate carried by the motor-shaft and provided with a pin, a disk carried by said spindle and formed with a slot through which said pin extends, a spring-arm secured to said disk and extending into engagement with 95 said pin, and a circuit-making-and-breaking brush carried by said plate, said brush moved in one direction by the tension of the winding-spring and in the other direction by the tension of the said spring-arm.

5. In combination, a driving-spring, an electric-motor for periodically energizing the same; a hollow shaft for the said motor; a driving-spindle extending through the said hollow shaft; a driving-pinion mounted at the forward end of the said spindle; an electric-circuit for the said motor; a switch-mechanism interposed in the said circuit and including two relatively-movable members, one of which is mounted upon the rear end of the said hollow shaft and the other of which is mounted upon the rear end of the said driving-spindle; and a switch-spring for yieldingly holding the said members against relative movement.

In testimony whereof, I have signed this specification.

UNO L. SUNDBLAD.
